UNITED STATES PATENT OFFICE.

GEORGE M. ALLERTON, OF NEW YORK, N. Y.

IMPROVEMENT IN LIFE-PRESERVERS.

Specification forming part of Letters Patent No. **79,934**, dated July 14, 1868.

To all whom it may concern:

Be it known that I, GEORGE M. ALLERTON, of the city, county, and State of New York, have invented a new and useful Improvement in Life-Preservers; and I do hereby declare that the following is a full, clear, and exact description thereof, reference being had to the accompanying drawings, making a part of this specification.

My invention consists in making an inflatable life-preserver in the form of a ring, and elastic, so that, being put on over the head and shoulders, it will clasp the person sufficiently tight to hold itself in place.

I make my improved life-preservers of two pieces of sheet-rubber cut in proper shape and of equal size. The edges of the two pieces are then joined, the inflating-tube A is attached, and then the life-preserver is subjected to the vulcanizing process.

Figure 1 represents one of my improved life-preservers, in which the cavity is continuous and of the same size all of the way round.

Fig. 3 represents one made much smaller in the parts that come under the arms than in those that cross the breast and back. The cavities may be made continuous all the way round, or they may extend only from arm to arm each way. In the latter case two inflating-tubes would be necessary.

My improved life preservers, when not inflated, occupy but little space. They can be inflated and put on almost instantly, and when once on it is impossible for them to get off by accident, as there are no strings to get untied or clasps to get unfastened. They are made in various forms, two of which only are shown in the drawings.

What I claim as my invention is—

An annular inflatable elastic rubber life-preserver, substantially as specified.

GEO. M. ALLERTON.
